UNITED STATES PATENT OFFICE.

GEORGE L. PIERCE, OF BROOKLYN, NEW YORK.

FOOT-BALL.

1,002,928.

Specification of Letters Patent. Patented Sept. 12, 1911.

Application filed June 21, 1911. Serial No. 634,500.

To all whom it may concern:

Be it known that I, GEORGE L. PIERCE, a citizen of the United States, residing at Brooklyn, in the county of Kings and State 5 of New York, have invented certain new and useful Improvements in Foot-Balls, of which the following is a specification.

My present improvement is an improvement 10 in foot balls, relating more particularly to the tongue of the ball. Perhaps the chief difficulty with foot balls is with the breaking of the bladder or rubber inflatable inside member. This usually occurs in the part 15 of the bladder which is at the mouth of the ball or at the inflating nipple, especially where it joins the bladder. It is the purpose of my present invention to remedy this defect by an improvement in the tongue of the ball to protect said portion of the bladder and nipple.

In the drawings wherein I have shown one specific embodiment of my invention, Figure 1 is a plan view of a foot ball embodying my improvement; Fig. 2 is a vertical section being a partial view on an enlarged scale corresponding to the upper portion of Fig. 3 except that the nipple is shown projecting upwardly in inflating position instead of laced down as in Fig. 3; 30 and Fig. 3 is a vertical section on the line 3—3 in Fig. 1 looking in the direction of the arrows, said section being on an enlarged scale and the nipple and the portions of the bladder at the base of the nipple being 35 shown in elevation.

I will now describe the devices of the drawings, reserving it to the claims to point out the novel features and to define the scope of the invention, it being understood 40 that the claims will be given the due range of equivalents to which they are entitled.

1 is the leather body of the ball having the usual mouth 2 adapted to be laced together.

45 3 is the bladder consisting of the usual rubber inflatable inside member having the nipple 4.

5 designates inside reinforcing strips secured at the sides of the mouth of the body 50 by stitching 6.

7 is the improved tongue consisting of an upper leather layer 7^a and a lower felt or soft pad layer 7^b. The tongue is held in place at the mouth of the body by stitching

8 attaching it thereto. The two layers are 55 united by stitching 9 and the padding layer at 7^b extends beyond the edges of the nipple opening in the leather layer to there protect the wall of the nipple from being cut through by contacting with said leather 60 edges. Further, the padding layer at its outer edges extends beyond and underlies the marginal edges of the leather layer of the tongue, thereby protecting the bladder from abrasive or cutting contact with said edges 65 and with the edges of the reinforcing strips 5.

Figs. 1 and 3 show the improved foot ball inflated and partially laced up and serve in connection with Fig. 2 clearly to show how 70 very effectually the improved tongue protects the bladder and nipple. Hitherto, the art has always considered merely the protection of the bladder and nipple from cutting by the lacing and has overlooked the 75 importance of protecting these parts from the tongue itself which is what the present improvement effects.

Having thus described my invention, what I claim is:

1. An improved foot ball comprising the combination of a body having a laced mouth, a bladder having an inflating nipple, a tongue within the body at its mouth, consisting of an upper leather layer and a lower 85 padding layer, said tongue having an opening through it for the nipple to project through, said padding layer projecting beyond the marginal edges of the leather layer and beyond the edges of the nipple opening 90 through said leather layer.

2. An improved foot ball comprising the combination of a body having a laced mouth, a bladder having an inflating nipple, a tongue within the body at its mouth consisting of an upper leather layer, and a lower 95 padding layer, said tongue having an opening through it for the nipple to project through, the padding layer extending beyond the edges of the nipple opening through 100 the leather layer.

In testimony whereof I affix my signature in presence of two witnesses.

GEORGE L. PIERCE.
